UNITED STATES PATENT OFFICE

2,523,430

RECIPROCATING DIE ACTUATING MEANS

Henry T. Hearn, Winston-Salem, N. C.

Application August 23, 1948, Serial No. 45,653

2 Claims. (Cl. 101—3)

1

This invention relates to an embossing machine, adapted to emboss names, symbols, and the like on the inner flaps of envelopes, stationery, cards, and similar stock.

By way of background, it may be noted that embossing of such stock as has been mentioned above is still most commonly carried on in the art by hand. Obviously, the use of a hand embosser is fatiguing, slow, and expensive, in view of the number of workers needed.

The primary object of the present invention, accordingly, is to provide an embossing machine, adapted to perform at high speed all the embossing operations presently being carried out by hand, said machine to require the presence of only one person, to feed the stock to the machine.

Another important object is to provide, in such a machine, adjustment means whereby the speed of the machine can be adjusted readily and simply, and to provide, in combination with the speed adjustment, a pressure adjustment whereby the force with which the embossing is accomplished can be varied.

Another important object is to provide a device as described that will comprise a compact, simply designed, and self contained unit, readily portable, and including an adjustably positioned power means, adjustable power transmission, and an embossing head so formed as to accommodate various types of conventional dies, such as spring steel dies, flat plates, and the like.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Figure 1 is a side elevational view of an embossing machine constructed in accordance with the invention, portions being broken away.

Figure 2 is a side elevation of the machine, looking at the opposite side.

Figure 3 is a top plan view.

Figure 4 is a fragmentary detail section, taken on line 4—4 of Fig. 2.

Figure 5 is a fragmentary section through the adjustable motor mount.

2

Referring to the drawings in detail, 10 designates a cast base, substantially flat and rectangular in general conformation. Cast on the base, at one end thereof, are the parallel guide rails 11, on which slides the platform 12 said platform adapted to be held firmly in adjustable positions to which slidably moved by means of the hold down bolts threadable into the guide rails 11 through the locking plates 14, that overlie the side flanges of the platform.

The motor 15 is bolted to the platform 12 and in view of the above described mounting of the platform, motor 15 is thus adapted to be adjusted transversely of the base 10, and secured in ad-

15 justed positions. To facilitate the adjustment, I provide an upstanding projection 16 on the base, having a threaded opening receiving the elongated adjusting screw 17, that is connected at its inner end to, and is rotatable in, an ear 20 depending from platform 12, as shown at 18 (Fig. 5).

The electric motor 15 is adapted to rotate a drive wheel 19, said drive wheel in the present instance being a smooth faced disc of substantial diameter, preferably formed of aluminum material or the like.

Frictionally engaging one face of the drive wheel 19, for rotation by the drive wheel, is the small friction roller 20, which is preferably rubber-covered, and the friction roller 20 is mounted to slide along and rotate with the non-circular shaft 21. Shaft 21 is journaled at one end in the bearing 22, fixedly secured to and upstanding from the base 10.

35 Rigid with and extended laterally from the bearing member 22 is the guide arm 23, having its free end upturned and formed with an opening in which is journaled one end of the speed adjustment screw 24, that is also journaled in the bearing member 22. Speed adjustment screw

40 24 is threadable in threaded opening formed in the fork 25, and thus, rotation of the screw is adapted to feed the fork 25 longitudinally of the non-circular shaft 21. The lower end of the fork 25, it may be noted, is mounted to slide along the guide arm 23.

The upper end of the fork is disposed in the annular groove of a groove collar 26 that is rigid with the friction roller 20. Accordingly, it may be observed that by rotation of the adjusted screw 24, the friction roller 20 can be adjusted to the

left or right in Fig. 1, for adjustment of the speed of said roller.

Mounted on and rotatable with the shaft 21 is the balance wheel 27, and the other end of the shaft extends into the cast gear case 28, having the removable cover plate 29. Said other end of the shaft carries the worm 30, in mesh with the gear 31, said worm and gear constituting reduction gearing.

Rotatable with the gear 31 is the driven disc 32, and connected at one end to the disc 32 is the pitman 33. The other end of pitman 33 is connected to toggle 34, that is pivoted at one end, as at 35, to the pedestal 36 upstanding from the base 10. The other end of the toggle is pivoted as at 37 to the lower end of the plunger 38, that is square in cross section, and is adapted to be reciprocated in the rear extension 39 of the standard 40, that extends upwardly from the pedestal 36. By reference to Fig. 4, it may be noted that the extension 39 is formed with recess 41 that is angular in cross section, in which recess the plunger 38 is adapted to be reciprocated, and normally covering said plunger and recess is the access plate 42, removably mounted on the extension 39.

The upper end of the plunger 38 is adapted to abut against the pressure adjustment screw 43, that is adjustably threaded through the rear end of a rocker arm 44, fulcrumed on the cross bar 45, that is mounted in the head 46 integral with the standard 40.

The other end of the rocker arm 44 engages the upper end of plunger block 47, reciprocable in the head 46. Thus, it may be observed that on the upstroke of the plunger 38, plunger block 47 will be impelled downwardly, and the pressure in which said plunger block is forced downwardly, that is, the length of said stroke, is adjusted by means of the pressure adjustment screw 43.

Adapted to return the plunger block to its normal position is the coil spring 48, and permitting removal of the plunger block 47 when desired is the removable access plate 49, mounted on the head 46 and defining in cooperation with the head a non-circular bore in which the plunger block 47 reciprocates.

Fixedly secured to the lower end of the plunger block 47 is the die plate holder 50, having formed at its underside the dovetail groove 51. A die plate 52 is formed with a tongue that fits in the groove 51, and thus, die plate 52 can be removed as necessary. On the die plate 52 is the transversely disposed pressure block 53, used when embossing operations are to be performed with spring seal dies (not shown).

Opposing and spaced from the die plate 52 is the lower die plate holder 54, which alternatively may be considered the male die holder. This supports the removable lower die plate or female die plate 55.

In the event spring seal dies are to be utilized, these are carried by an adjustable holder to be described. Referring to this holder, a bolt 56 extends through slots formed in the holder 57, that is formed with the opening 58. Opening 58 is adapted to receive holding screw, not shown, that supports the female or upper spring seal die in a position just below the pressure block 53. The male spring seal die, as will be understood, is adapted to rest upon the male die plate holder 55. By means of the slotted holder 57, adjustment of the spring seal die relative to the pres-

sure block 53 can be made before the die is secured in position below the pressure block.

The operation, it is believed, will be readily understood. The operator feeds individual pieces of stock into the space between the dies, in succession, and in rhythm with the movement of the plunger block 47. The number of strokes per minute of plunger block 47 are readily adjusted by means of the speed adjustment screw 24. The length of stroke or pressure of the stroke of the plunger block 47 is adjusted by means of the pressure adjustment screw 43. Assuming that all adjustments have been made, the user, if spring seal dies are to be used, secures the female die to the holder 57 as described above, and adjusted relative to the pressure block 53. The male spring seal die is secured upon the removable male die plate holder 55. Embossing operations may now be carried on at regulated speed and pressure.

If dies other than spring seal dies are to be used, as for instance where flat plates are being used, the female die plate can be formed with a tongue adapted to fit in the dovetail groove 51, it being understood that the die plate holder 52 would of course in this instance be removed. A cooperating male die would be substituted for the holder 55. Other dies of various thicknesses can be utilized, and in each instance, adjustments can be made for the machine to accommodate the particular type of die being used, and also to accommodate the working speed of the operator. In every instance, a legible embossed impression is made, and the various adjustments mentioned permit minute regulation so as to make said impression not only legible, but of maximum clarity.

What is claimed is:

1. In an embossing machine a base; a stationary die holder mounted thereon; a plunger block including a die holder complementary to the stationary die holder and mounted for vertical sliding movement in said base; spring means interposed between the plunger block and base and normally biasing said plunger block away from the stationary die holder; a rocker arm pivotally mounted intermediate its ends upon the base, the pivotal connection of said rocker arm to the base being closer to one end of said rocker arm than to the other end thereof for movement of opposite ends of the rocker arm through arcuate paths of different lengths, one of said ends of the rocker arm overlying said plunger block for biasing the plunger block downwardly toward said stationary die holder; an adjusting screw threaded in the other end of said rocker arm; a plunger rod slidably reciprocable in said base and engaging said adjusting screw at one end; and means for imparting reciprocating movement to said plunger rod.

2. In an embossing machine a base; a stationary die holder mounted thereon; a plunger block mounted for vertical reciprocation in said base and including a movable die holder complementary to the stationary die holder; spring means interposed between the plunger block and base and normally biasing the plunger block upwardly away from said stationary die holder; a rocker arm pivotally mounted upon the base intermediate its ends, the pivotal connection of said rocker arm being disposed closer to one end thereof than to the other end, the first-named end of the rocker arm overlying and being non-connected to the plunger block for biasing the plunger block downwardly toward the stationary die holder on swing-

ing of said first-named end of the rocker arm through an arcuate path, there being a threaded opening formed in the opposite end of said rocker arm; an adjusting screw threaded in said opening; a plunger rod mounted for sliding reciprocating movement in the base and engaging said adjusting screw at one end for imparting rocking movement to said rocker arm against the action of the spring; and means for imparting reciprocating movement to said plunger rod.
